[57] CLAIM

The ornamental design for a lawn sign, as shown and described.

DESCRIPTION

FIG. 1 is a perspective view of a lawn sign showing my new design;

FIG. 2 is a view from one side thereof;

FIG. 3 is a view from the opposite side thereof;

FIG. 4 is an elevational view of the left side of FIG. 2. FIG. 5 is an elevational view of the opposite side thereof.

FIG. 6 is a fragmentary enlarged view taken along lines 6—6 of FIG. 5.
